UNITED STATES PATENT OFFICE

2,295,549

CAR TRUCK

Robert B. Cottrell, Chicago, Ill., assignor to
American Steel Foundries, Chicago, Ill., a corporation of New Jersey

Application December 20, 1940, Serial No. 370,912

19 Claims (Cl. 105—197)

My invention relates to railway car trucks and more particularly to snubbing and stabilizing means which are designed to improve greatly the riding qualities thereof.

In my co-pending application, Serial No. 347,453, filed in the United States Patent Office July 25, 1940, I have described a somewhat similar form of stabilizing means which is applied to a spring plankless quick wheel change truck such as that shown in my Patent No. 2,188,641. My present invention involves the application of a generally similar stabilizing or snubbing device to what is commonly known as a conventional A. A. R. railway car truck having spaced side frames and a spring plank and a bolster extending therebetween.

An object of my invention is to design stabilizing and snubbing means for application to such a conventional railway car truck wherein wear between the bolster gibs and the guide columns on the side frame is reduced to a minimum.

A further object of my invention is to devise a stabilizing device for a railway car truck wherein out-of-square movements of the bolster and side frames are resisted by novel means operable outboard each side frame.

Another object of my invention is to apply snubbing means outboard the side frames of a railway car truck to prevent synchronous oscillations of the bolster supporting spring group and thus greatly reduce damage to lading carried in the car body.

My invention contemplates snubbing vertical oscillations of the bolster by a device wherein the energy absorbed by friction is substantially constant and uniform.

A different object of my invention is to design stabilizing means which are so connected to the bolster and side frames that the outboard gibs on the bolster may be omitted and the means will serve to cushion and take lateral thrusts of the bolster against the side frames.

A specific object of my invention is to apply to a conventional railway car truck stabilizing means comprising a ride control bar secured to an end of the bolster and extending along the outboard faces of the adjacent guide columns of the side frame, each end of said bar having associated therewith resilient pads and friction shoes confined between a housing and the outboard face of the guide columns, said resilient pads pressing said shoes against the housing and the guide column for substantially uniform frictional absorption upon relative vertical movement of the bolster and side frames.

In the drawings,

Figure 1 is a fragmentary half side elevation of a car truck embodying my invention, the other half of said truck not being shown because it is similarly arranged.

Figure 2 is a top plan view of the car truck shown in Figure 1.

Figure 3 is a fragmentary sectional view of the car truck shown in Figure 1, the section being taken substantially in the vertical transverse plane bisecting the car truck as indicated by line 3—3 of Figure 1.

Figure 4 is a fragmentary sectional view of the snubbing means associated with each column, the section being taken substantially in the vertical transverse plane indicated by the line 4—4 of Figure 1.

Figure 5 is a side elevation of the ride control bar used in the device shown in Figure 1. Figure 5A is a top view of said bar, and Figure 5B is an end view thereof.

Figure 6 is a fragmentary half side view of a car truck embodying a different modification of my novel invention, the other half of said car truck not being shown because it is similarly arranged.

Figure 7 is a fragmentary top plan view of the car truck shown in Figure 6.

Figure 8 is a fragmentary sectional view of the car truck shown in Figure 6, the section being taken substantially in the vertical transverse plane bisecting the car truck as indicated by the line 8—8 of Figure 6.

Figure 9 is a side view of the ride control bar used in the modification shown in Figure 6.

Figure 9A is a top plan view of the bar shown in Figure 10, and Figure 9B is an end view thereof.

Figure 10 is a fragmentary sectional view of a different modification of the snubbing means applied outboard each column, the section being taken substantially in the same plane as that of Figure 4.

In the modification shown in Figures 1 to 5, inclusive, the railway car truck includes spaced side frames each comprising a top compression member 2 and a bottom tension member 4 merging at their ends with journal means (not shown) which afford a connection to supporting wheel and axle assemblies (not shown) in usual manner. At each side of the bolster opening 6 may be formed a bolster guide column 8 having a relatively wide outboard face, and outwardly of each column 8 is formed a window opening 10.

A seat 12 for a side bearing (not shown) is afforded on the bolster 14 adjacent to each side

frame, and a bolster end 18 is accommodated in the bolster opening 6 and seated on a spring group of any convenient arrangement. The spring group comprises a top spring cap 20 and a bottom cap 22, each having flanges along each edge serving as retaining means for the adjacent ends of coil springs generally indicated at 24, 24. The bottom spring cap 22 is seated as at 27 on an end of the spring plank 26 which extends between the side frames and bears as at 28 against the widened top wall 30 of the tension member 4 which affords a spring seat portion. The bolster 14 and each column 8 are afforded complementary guide faces as at 32, and the bolster is afforded inboard and outboard gibs or guide lugs 34 and 36, respectively, which in the conventional truck normally take lateral thrusts of the bolster against the side frames. Each guide column 8 is relieved at its lower portion as at 38 to permit passage of the outboard gib 36 in assembly and dismantling of the bolster and side frames.

A central rib 40 reinforces the generally box section bolster end 18, and at each outboard corner said end 18 is afforded a vertical transverse wall 42 extending between the top and bottom walls 44 and 46 respectively of the bolster and integrally formed with said walls and the adjacent side wall 45. Above each wall 42 the top wall 44 extends outboardly thereof to afford a lug 48, and below each wall 42 the bottom wall 46 is projected outboardly to form a bottom lug 50. On each bottom lug 50 a vertical upstanding flange 52 is formed along its outboard edge, and each lug 50 may be relieved as at 54 to afford convenient means for assembling the ride control bar or member 56 between the top and bottom lugs 48, 48 and 50, 50 on the bolster. The bar 56 is seated on the bottom lugs 50, 50 and is tightly retained against the walls 42, 42 in any suitable manner as by nut and bolt assemblies 58, 58 extending through aligned openings in said bar and said walls 42, 42. The bar and the bolster end thus act as a unit.

The ride control bar 56 is shown in detail in Figures 5, 5A, and 5B, and comprises a relatively long rectangular bar having intermediate its ends a generally channel section afforded by the top and bottom reinforcing flanges 60, 60. Each end 61 of the bar extends outboard and along the adjacent column 8, and is afforded on opposite faces thereof positioning lugs 62, 62.

Adjacent to the window opening 10 and on the outboard face of each column 8 may be a friction device with which is operatively associated an end 61 of the ride control member 56. Seated against opposite faces of each end 61 and positioned on said lugs 62, 62 may be resilient pads 64, 64 of any suitable material. On the opposite faces of said pads 64, 64 are seated and positioned by lugs 72, 72 the friction shoes 66, 66 which are of a form fully described in said pending application. Briefly, each shoe 66 is identical and is afforded at one end a central lug 68. At the opposite end of each shoe are formed spaced lugs 70, 70 between which is received the central lug 68 on the adjacent shoe. Flanges 74, 74 along opposite edges of each shoe afford guide means for said shoes along a housing 76 and a wear plate 78 respectively, said wear plate being seated against the outboard face of column 8. The wear plate 78 is afforded abutment at 80 with a retaining lug 81 formed adjacent to the top of the compression member and is seated as at 82 on the bottom wall 84 of housing 75

76. A lug 86 on the bottom wall 84 extends within an opening 88 in the outboard wall of column 8 and is formed with a downwardly projecting portion 80.

5 In assembly, after the parts are positioned on each end 61, the lug 86 is inserted into the opening 88 and the housing 76 is rotated upwardly about the fulcrum lug 86 and secured at its upper end by a pin 92 extending through spaced lugs 84, 84 formed adjacent to the top member 2 and lugs 86, 86 on the top of housing 76.

It is apparent that when the housing 76 is secured in place, the shoes 66, 66 are urged into engagement with the housing 76 and the wear plate 78 respectively by the resilient pads 64, 64 which are compressed between said shoes and the end 61 of the bar 56. The top and bottom edges of each end 61 are afforded slight clearance at 88, 88 from the adjacent lugs on the shoes 66, 66 and as the bolster oscillates vertically each end abuts the adjacent lugs and moves the shoes in sliding frictional engagement along the housing 76 and wear plate 78. It is apparent that the energy absorbed by said frictional engagement will be substantially constant and uniform throughout vertical movement of the bolster with respect to the side frames. Synchronous vibrations of the bolster are thus substantially eliminated.

30 The amount of energy absorbed may be varied by changing the pre-compression of the resilient pads 68, 68 or by changing their size, shape, and composition. The maximum compression of the pads, as well as the amount of lateral and out-of-square movement of the bolster, is controlled by clearance at 100, 100 between lugs 62, 62 and 12, 12 on the end 61 and on shoes 66, 66 respectively.

40 Relative lateral movement between the bolster and side frame is cushioned by further compression of the resilient pads and wear between the bolster and the guide columns is reduced to a minimum.

45 By placing the friction devices on the guide columns adjacent to the window openings 10, 10, and affording a relatively long ride control bar, I have devised effective means for cushioning and resisting out-of-square movement of the bolster with respect to the side frames. Such movement of the bolster will cause further compression of the resilient pads and said pads will act to restore the bolster to its proper relationship with the side frames.

55 In the modification shown in Figures 6 to 9, the ride control bar is interlocked and secured to the end of a bolster in different manner from that previously described. The side frame comprises a top compression member 102 and a bottom tension member 104 defining with bolster guide columns 106, 106, a bolster opening 108. Beneath the bolster opening 108 the top wall 110 of the bottom tension member may be widened to form a spring seat 111, and seated on said spring seat may be a spring plank 112 extending between the side frames. A bottom spring cap 114 seated on the spring plank 112 and a top spring cap 116 afford retaining means for adjacent ends of the spring arrangement diagrammatically indicated at 118. The end 120 of the bolster 122 is seated as at 124 on the top spring cap 116, and is afforded inboard and outboard guide lugs 126, 126 and 128, 128 respectively. Each column 106 is relieved adjacent its lower end at 130 to permit passage of the out-

board guide lug 128 in assembly and dismantling of the bolster and side frame.

A central rib 132 reinforces the bolster end 128, and the bottom wall 134 of the bolster may be formed with an offset transverse wall 136 at its outboard end. Interposed between the offset wall 136 and the spring cap 116 may be a horizontal wall 138 of the ride control bar 140, said wall 138 having its bottom surface coplanar with the surface on the bottom wall 134 of the bolster 122. The ride control bar 140 is shown in detail in Figures 9, 9A, and 9B, and on the wall 138 may be formed spaced upwardly projecting lugs 142, 142 which are accommodated in spaced aligned complementary openings 144, 144 in the offset wall 136 to interlock the bar 140 with the bolster. The vertical wall 146 and the horizontal wall 138 are reinforced by the spaced triangular ribs 148, 148 which are accommodated outwardly of offset portions 150, 150 of the side walls 152, 152 of the bolster. The outer surfaces of said ribs 148, 148 are coplanar with the outer face of the side walls 152, 152 and it is apparent from a consideration of Figures 7 and 8 that only a relatively small portion of the ribs 148, 148 may be subjected to wear against the guide columns 106, 106 in operation. The vertical wall 146 is afforded a longitudinally extending outboard reinforcing rib 154 having tapered ends terminated short of the ends of the bar 140. Each end 156 of the vertical wall 146 is afforded positioning lugs 158, 158 on opposite faces thereof for resilient cushioning pads 160, 160 associated with a friction device on the outboard face of each column 106 and spaced from the bolster opening 108.

The friction device is substantially identical to that described in the previous modification and includes friction shoes 162, 162 seated against and positioned on the opposite faces of said pads 160, 160 in frictional engagement with a housing 164 and a wear plate 166 respectively. The assembly and manner of connection of the housing 164 with the column 106 is identical with that previously described.

In this modification I have shown a novel manner of connecting the ride control bar to the outboard end of a bolster wherein the bar is securely retained in place by pressure from the spring group and the interlocking lugs 142, 142, so that the bolster end and bar act as a unit. It is apparent that the operation of this modification is substantially the same as that described for the first modification.

In Figure 10 is shown a different modification of the friction device on the outboard face of each column, and it is understood that it may be used with either arrangement previously described. It may be noted that the outboard wall 180 of the guide column flares outwardly and downwardly, and the outer wall 182 of the housing 184 flares downwardly and inwardly so that the walls 180 and 182 converge toward the bottom. The friction shoes 186, 186 are identical with those previously described except that the outer faces thereof are afforded complementary diagonal face engagement with the adjacent walls 180 and 182 respectively. The resilient pads 188, 188 are compressed between the shoes and the adjacent end of the ride control bar as previously described. It is apparent that in the modification shown in Figure 10, as the bolster moves downwardly the frictional resistance between the shoes and the walls 180 and 182 will

increase because of their converging arrangement.

It will be understood by those skilled in the art that the outboard guide lugs or gibs may be omitted from the bolster end and the ride control bar with the snubbing device on each column will cushion and take lateral thrusts of the bolster with respect to the side frames. In this latter arrangement assembly and dismantling of the bolster and side frame is greatly facilitated because the bolster may be removed from the bolster opening without first removing the spring group by disengaging the ride control bar with the snubbing device on each column and removing said bar from its interlocking engagement with the bolster.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a side frame having a compression member, a tension member, and spaced columns defining with said members window openings and an intermediate bolster opening, spring means on said tension member, a bolster end seated on said spring means in said bolster opening with inboard and outboard guide lugs engaging said columns, spaced retaining means adjacent opposite corners of said bolster end, cushioning means outboard said columns adjacent said window openings, each of said cushioning means including spaced friction surfaces, shoes engaging said surfaces, and resilient means abutting said shoes, and a member extending parallel with said side frame and interlocked by said retaining means with said bolster end, said interlocked member being operatively associated at its ends with said resilient means for cushioning relative movement of said bolster end and said side frame.

2. In a railway car truck, a side frame having a compression member, a tension member, and spaced columns defining with said members window openings and an intermediate bolster opening, spring means on said tension member, a bolster end extending into said bolster opening with inboard and outboard lugs engaging said columns and seated on said spring means, spaced retaining means adjacent opposite corners of said bolster end, cushioning means outboard said columns adjacent said window openings, each of said cushioning means including spaced friction surfaces supported on said columns, shoes engaging said surfaces, and resilient means compressed against said shoes, and a member extending along said side frame and interlocked with said retaining means and operatively associated with said resilient means whereby wear between said bolster end and said columns is reduced to a minimum.

3. In a railway car truck, a side frame having a compression member, a tension member, and spaced columns defining with said members window openings and an intermediate bolster opening, spring means on said tension member, a bolster end seated on said spring means in said bolster opening with inboard and outboard lugs engaging said columns and presenting an offset bottom wall at its outer end, cushioning devices outboard said columns adjacent said window openings, each of said devices including spaced

friction surfaces, friction shoes engaging said surfaces, and resilient means abutting said shoes, and an actuating member fixed on said bolster end and extending along said side frame and operatively associated with said resilient means.

4. In a railway car truck, a side frame having a compression member, a tension member, and spaced columns defining with said members window openings and an intermediate bolster opening, spring means on said tension member, a bolster end seated on said spring means in said bolster opening with inboard and outboard guide lugs engaging said columns, spaced retaining means adjacent opposite corners of said bolster end, cushioning means outboard said columns adjacent said window openings, each of said cushioning means including spaced friction surfaces supported on said columns, shoes engaging said surfaces, and resilient means abutting said shoes, and actuating means interlocked with said retaining means and operatively associated with said resilient means for resisting out-of-square movement of said bolster end and said side frame.

5. In a railway car truck, a side frame having spaced columns and an intervening bolster opening, a bolster extending into said opening and having outwardly projecting means, a member seated on certain of said means and secured to said bolster, said member having wing portions extending along said columns, spaced friction surfaces supported on each column, friction shoes engaging said surfaces, and resilient pads compressed between each wing portion and the adjacent shoes.

6. In a railway car truck, a side frame having top and bottom members and spaced columns defining a bolster opening, spring means on said bottom member, a bolster having an end extending into said opening with inboard and outboard guide lugs engaging said columns, a member fixed on the end of said bolster, said fixed member having wing portions extending along said columns, spaced friction surfaces supported on each column, friction shoes engaging said surfaces, and resilient pads compressed between each wing portion and the adjacent shoes.

7. In a railway car truck, a side frame having a compression member, a tension member, and spaced columns defining with said members window openings and an intermediate bolster opening, spring means, a bolster end seated on said spring means in said bolster opening and presenting transverse vertical walls, friction devices on the outboard faces of said columns adjacent said window openings, and an actuating bar extending along said side frame and secured against said walls and operatively associated with said devices.

8. In a railway car truck, a side frame having a compression member, a tension member and spaced columns defining a bolster opening, friction devices supported outboard said columns, a bolster end supported in said opening and presenting vertical transverse walls, top and bottom projecting lugs on said end adjacent to said walls, and a bar received between said lugs and secured against said walls, said member having end portions extending along said columns and associated with said friction devices.

9. In a railway car truck, a side frame having spaced columns and an intervening bolster opening, a bolster end received within said opening, resiliently supported from said frame, and having spaced outwardly projecting means at opposite

corners thereof, a member accommodated between said spaced means and secured to said bolster end, said member having wing portions extending along said columns, spaced friction surfaces supported on each column, friction shoes engaging said surfaces, and resilient pads compressed between each wing portion and the adjacent shoes.

10. In a railway car truck, a side frame having a compression member, a tension member and spaced columns defining a bolster opening, friction devices supported outboard said columns, a bolster end supported in said opening and having spaced lugs extending outwardly therefrom, a member interposed between said lugs and secured to said end, said member having ends projecting along said columns and cooperatively connected at all times to said friction devices.

11. In a railway car truck, a side frame having a compression member, a tension member and spaced columns defining a bolster opening, friction devices supported outboard said columns, a bolster end supported in said opening and having outwardly projecting means, a member seated on certain of said means and secured to said bolster end, said member having ends interengaged with said devices for actuation thereof upon relative movement of said bolster and said side frame.

12. In a railway car truck, a side frame having top and bottom members and spaced columns defining a bolster opening, a spring plank, a spring group on said plank in said opening, a bolster end supported on said spring group, friction means mounted outboard each of said columns, and an actuating bar fixed on the end of said bolster with end portions engaging said friction means for actuation thereof.

13. In a railway car truck, a side frame having top and bottom members and spaced columns defining a bolster opening, a spring plank, a spring group on said plank in said opening, a bolster end supported on said spring group, friction means mounted outboard each of said columns, and an actuator fixed on the end of said bolster with wing portions engaging said friction means for actuation thereof, said actuator comprising a vertical web secured to said bolster and comprising positioning means at opposite ends thereof for resilient pads associated with said friction devices.

14. In a railway car truck, a side frame having top and bottom members and spaced columns defining a bolster opening, a spring group in said opening, a bolster end supported on said spring group, friction means mounted outboard each of said columns, and an actuator fixed on the end of said bolster with wing portions engaging said friction means for actuation thereof, each of said friction means comprising a friction panel in abutment with the adjacent column, a spaced friction panel, interlaced friction shoes abutting respective panels, and resilient means under compression between the respective friction shoes and an adjacent portion of said actuator.

15. In a railway car truck, a side frame having top and bottom members and spaced columns defining a bolster opening, a spring group in said opening, a bolster end supported on said spring group, friction means mounted outboard each of said columns, and an actuator fixed on the end of said bolster with wing portions engaging said friction means for actuation thereof, each of said friction means comprising spaced diverging friction surfaces, interlaced friction shoes engaging the respective surfaces, and resilient means under

compression between each shoe and an adjacent portion of said actuator.

16. In a railway car truck, a side frame having top and bottom members and spaced columns defining a bolster opening, a spring group in said opening, a bolster end supported on said spring group, friction means mounted outboard each of said columns, and an actuator fixed on the end of said bolster with wing portions engaging said friction means for actuation thereof, each of said friction means comprising spaced diverging friction surfaces, a friction shoe engaging each surface and resilient means under compression between each shoe and an adjacent portion of said actuator.

17. In a railway car truck, a side frame having top and bottom members and spaced columns defining a bolster opening, a bolster end projecting into said opening in guiding relation with said columns, friction devices mounted outboard of said columns, and operating means fixed on said bolster end with end portions actuating said friction devices, each of said friction devices comprising opposed diverging friction surfaces, a friction shoe seated against each surface, and resilient means compressed between each shoe and the adjacent portion of said operating means.

18. In a railway car truck, a side frame having a bolster opening, a spring plank, resilient means on said plank in said opening, a bolster end supported on said resilient means, spaced friction means mounted on said frame, each of said friction means comprising spaced friction surfaces, a friction shoe in engagement with each surface, and a resilient member urging said shoe into said engagement, and an actuating member associated with said end and comprising wing portions, each of said portions operating one of said friction means and being connected between the resilient members associated therewith.

19. In a railway car truck, a side frame having a bolster opening, a spring plank, resilient means on said plank in said opening, a bolster end supported on said resilient means, a friction device mounted on said frame and comprising opposed friction surfaces, friction shoes having friction faces abutting said surfaces respectively, resilient means urging said shoes into tight engagement with said surfaces, and an actuator associated with said bolster end and connected between said resilient means for actuation of said shoes.

ROBERT B. COTTRELL.
